US00D763298S

(12) **United States Design Patent**
Hoang et al.

(10) **Patent No.:** **US D763,298 S**
(45) **Date of Patent:** **** Aug. 9, 2016**

(54) **DISPLAY SCREEN WITH GRAPHICAL USER INTERFACE**

(71) Applicant: **Microsoft Corporation**, Redmond, WA (US)

(72) Inventors: **Peter Duyen Hung Hoang**, Delta (CA); **Darren Woo**, Redmond, WA (US); **Stephen Wolynsky**, Redmond, WA (US); **Tad Natsuhara**, Redmond, WA (US); **Tyler Bielman**, Redmond, WA (US)

(73) Assignee: **Microsoft Corporation**, Redmond, WA (US)

(**) Term: **14 Years**

(21) Appl. No.: **29/500,802**

(22) Filed: **Aug. 28, 2014**

(51) **LOC (10) Cl.** **14-04**

(52) **U.S. Cl.**

USPC **D14/487**

(58) **Field of Classification Search**

(57) **CLAIM**

The ornamental design for a display screen with graphical user interface, as shown and described.

DESCRIPTION

FIG. 1 is a front view of a display screen with graphical user interface showing our new design; and,

FIG. 2 is a front view of a display screen with graphical user interface showing an alternative view of our new design. The broken line showing of the text, the icons, the remainder of the user interface and the remainder of the display screen is for environmental purposes only and forms no part of the claimed design.

1 Claim, 2 Drawing Sheets
